UNITED STATES PATENT OFFICE.

JOHN A. BUTKUS, OF BALTIMORE, MARYLAND.

FREIGHT-ELEVATOR.

1,163,391.

Specification of Letters Patent. Patented Dec. 7, 1915.

Application filed May 4, 1914. Serial No. 836,360.

To all whom it may concern:

Be it known that I, JOHN A. BUTKUS, a citizen of the United States of America, residing at Baltimore, Maryland, have invented certain Improvements in Freight-Elevators, of which the following is a specification.

This invention relates to certain improvements in what are known as freight elevators, that is to say elevators in which a platform instead of a passenger car is used; and it consists in means whereby a door having a closing spring attached thereto and leading to a floor of the building, if opened, remains open until the platform of the elevator has passed the door in an upward or a downward direction, when the door is closed, but not held closed in such manner as to prevent its reopening at any time, as will hereinafter fully appear.

In the further description of the said invention which follows, reference is made to the accompanying drawings, forming a part hereof, and in which:

Figure 1 is a face view of the improved apparatus, together with a part of the walls of the elevator well, and a portion of the floor of the building; and Fig. 2 is a view of Fig. 1 looking in the direction indicated by the arrow in that figure. Fig. 3 is a section taken on the broken line $x-x$ in Fig. 1. Fig. 4 is an enlarged view of certain parts shown in Fig. 2, and Figs. 5, 6 and 7 are enlarged details of the apparatus and hereinafter described.

Referring now to the drawings, 1 represents the well opening, and 2, 2 the walls thereof.

3 is a part of a hinged door leading from the elevator well to a floor 4 of the building. The hinges which secure the door to the front wall of the well are not shown.

5 is an angular plate shown as secured to the front and one of the side walls of the well, and 7 a shaft adapted to slide endwise in lugs a on the face of the plate.

10 is a linked hinge which unites the door 3 with the outer end of the shaft 7.

12 is a rockshaft supported at one of its ends by the angular plate 5, and at its other end by a bracket 13.

14 is a leaf spring fastened to the under side of the plate 5 with its free end situated between the pins b projecting from the horizontally moving bolt 15 which is adapted to slide in the angular plate 5, and a bracket c

extending therefrom. The function of the spring 14 is to yieldingly hold the projecting end of the bolt 15 in the path of the sliding shaft 7, and when so situated, serves as a stop for the said shaft, as shown in Fig. 2 of the drawings, and thereby prevent the open door 3 which is hinged to the shaft 7 as before stated, being closed.

17 is a small flat plate secured in any suitable manner to the shaft 12, and it rests on the leaf spring 14 for a purpose hereinafter described.

20 is the movable platform of the elevator.

23 is an arm loose on the shaft 12, with its hub portion cut away to receive a pin d which projects from the shaft, as best shown in Figs. 2 and 5.

24 is a spring coiled about the shaft 12 with one of its ends attached to the arm 23 and its other end fastened to the shaft. By this construction the arm is held tightly in contact with the pin d which prevents its movement independently of the shaft in one direction but admits of a limited movement independently of the shaft in a contrary direction, for a purpose hereinafter described. The free end of the arm 23 is provided with a roller 26.

In order that the arm 23 may be slightly compressible, endwise, for a purpose hereinafter explained, it is constructed in three principal parts viz. a bar e , a tubular shell f and a coiled spring g as shown in Fig. 5. The spring g , at one of its ends bears against the bar e and at its other end against a pin h ; and the shell is slotted, and the bar provided with a pin which allows of the endwise contraction of the arm while preventing rotative movement of the shell. An upward movement of the arm 23 causes an extension of the spring g .

Tight on the shaft 12 and leading rearward in a horizontal direction, is a bar 27 to the end of which is jointed the bent rod 30 which extends downward, and, in circumstances hereinafter stated, serves to communicate a partial rotary movement to the shaft 12 through the agency of mechanism now to be described.

23¹ is an arm in general construction similar to the arm 23, pivoted at i to a bracket 32 which is fast to the elevator wall, and at a suitable distance below the floor 4. At a point between the pivot i and the roller 26¹ is a sheave 29 which rests upon the bent

portion of the rod 30, as best shown in Fig. 3. A coiled spring 35 retains the arm 23¹ yieldingly in a horizontal position.

Referring now to Figs. 2, 3, 4 and 7, it will be understood that when the arm 23 is yieldingly held in a horizontal position as shown in Fig. 3, and the bolt 15 projected outward its end serves as a stop for the shaft 7, and prevents the closing of the door 3, 10 but should the said arm be raised, the plate 17 assumes an oblique position as shown in Fig. 7 and its edge forces the leaf spring inward carrying with it the bolt 15, and upon the end of the bolt becoming flush with the inner surface of the said shaft it no longer serves as a stop, and the door spring 37 shown only in Fig. 2 will cause the door to close; but there is nothing to prevent the door being again opened and held open until 15 in the operation of the apparatus the bolt 15 is again rendered inoperative.

Supposing the various parts of the apparatus to be in the positions shown in Figs. 1, 2 and 3 with the elevator platform 20 in a vertical position about central between the arms 23 and 23¹, the door 3 open, and the platform to be moving upward, the contact of the platform with the roller 26 will cause the arm 23 to rise which effects a partial rotation of the shaft 12. In the rotation of the said shaft, the plate 17 will be turned, and upon its reaching the proper degree of angularity the depression of the spring 14 will cause the withdrawal of the bolt 15 from contact with the shaft 7 and the door 3 will be automatically closed. After the platform has passed the arm 23 that device will assume its original position; and in view of the slotted construction of its hub portion, a 35 downward movement of the platform merely presses the arm downward, without causing any operation of the bolt 15. But should the platform occupying its original position between the arms 23 and 23¹ be lowered instead of elevated, the arm 23¹ will be downwardly tilted, and due to its sheave 29 resting upon the bent end of the rod 30 which is connected to the bar 27, the shaft 12 will be partially rotated but in a direction contrary 40 to that taken in the former case, and the stop bolt 15 being withdrawn from contact with the end of the shaft 7, the door will be closed in the manner before described.

From the above description of the operation of the invention it will be understood that the arm 23 is only operative to effect any useful result, upon the elevation of the platform, and the arm 23¹ in the downward movement of the same; and that the appliances used to perform the operations described do not prevent the opening of the door 3 at any time, but when the door is opened it cannot be closed except automatically in the manner described, or by the 45 manipulation of the arms 23 and 23¹ by hand

by a person standing on the platform, or upon the floor.

The object in making the arms 23 and 23¹ compressible endwise as described, is to prevent their subjection to injurious strain by 70 the platform when the same strikes their rollers from either direction; and also to obviate very nice adjustment of the said arms with respect to the edge of the platform.

I claim as my invention:—

1. In an elevator, the well thereof provided with a spring-closing door, a vertically moving elevator platform within the well, a plate secured within the well, a sliding shaft supported by the plate which is linked to the door and adapted when extended outward to hold the door open, and a stop for the sliding shaft, combined with appliances which receive their movement from the platform, to render the stop inoperative, and thereby admit of the automatic closing of the door. 75

2. In an elevator, the well thereof provided with a hinged door leading therefrom, a supplemental hinge on the door, a sliding shaft within the well to which the supplemental hinge is pivoted, stop mechanism for the sliding shaft to retain the door in an open condition, and a vertically moving platform within the well, combined with devices actuated by the platform when moving in an upward or a downward direction adapted to render the said stop mechanism inoperative and thereby admit of the closing of the door. 90

3. In an elevator, the well thereof having a door provided with a closing spring, a supplemental hinge on the door, a sliding shaft connected to the supplemental hinge which has a motion in common with the door in the opening and closing of the same, and a stop for the sliding shaft which prevents the closing of the door, combined with devices actuated by the platform in its upward or downward movement to render the said stop inoperative and thereby admit of the automatic closing of the door. 100

4. In an elevator, the well thereof provided with a spring backed door leading therefrom, a vertically moving platform in the well, a fixed plate situated in the well, a sliding shaft journaled in the plate, a supplemental hinge which unites the door with the sliding shaft, a spring-held bolt adapted to engage with, and to be disengaged from the said shaft and which when in the former position, serves as a lock for the open door, combined with pivoted arms which extend into the path of the moving platform, and appliances which derive their movement from the said arms, to coöperate with the locking mechanism to render the same inoperative and thereby allow the door to automatically close. 115

5. In an elevator, the well thereof provided with a spring-backed door leading therefrom, a vertically moving platform in 120

the well, a fixed plate situated in the well, a sliding shaft journaled in the plate, a supplemental hinge which unites the door with the sliding shaft, a spring-held bolt adapted 5 to engage with, and to be disengaged from the said shaft which bolt when in the former position serves as a lock for the open door, combined with pivoted arms in different vertical position which extend into the path of

the moving platform, and appliances which 10 derive their movement from the said arms and coöperate with the locking mechanism to render the same inoperative and allow the door to automatically close.

JOHN A. BUTKUS.
